P. H. HARTMAN

HOD

Filed Oct. 5, 1920

INVENTOR
Peter H. Hartman
BY
John A. Schlesinger
ATTORNEY

UNITED STATES PATENT OFFICE.

PETER H. HARTMAN, OF EAST ORANGE, NEW JERSEY.

HOD.

Application filed October 5, 1920. Serial No. 414,881.

To all whom it may concern:

Be it known that I, PETER H. HARTMAN, a citizen of the United States, and resident of East Orange, county of Essex, and State 5 of New Jersey, have invented certain new and useful Improvements in Hods, of which the following is a specification.

My invention relates to hods for carrying brick, mortar, plaster and the like and has 10 for its object to provide a hod of simple construction which may be easily and quickly taken apart when not in use, for storage, for instance, in a mason's tool bag or kit or for transportation from place to place and 15 which may be readily set up to provide an efficient carrier for bricks or the like or for mortar, plaster or other semi-liquid materials without leakage of the latter and without causing discomfort to the hod carrier. 20 My invention will be fully described herein-after and the features of novelty will be pointed out in the appended claims.

In the accompanying drawings, which 25 illustrate a specific embodiment of the invention without defining its limits, Fig. 1 is a side elevation of the hod; Fig. 2 is a sectional view on the line 2—2 of Fig. 1; Fig. 3 is a detail view illustrating a variation in the construction of the hod and Fig. 30 4 is a fragmentary view of the staff.

As illustrated in the drawings the hod comprises a fork 5 which is provided with a screw threaded stem 6 for connection, through the medium of a suitable coupling 35 7 with a post or staff 8 which itself is preferably constructed in sections detachably connected with each other in any convenient manner as for instance by means of couplings similar to the coupling 7. In order 40 to prevent unintentional separation or loosening of the parts a set screw 7^a may be provided which by bearing against the stem 6 prevents rotation of the coupling 7. A main section 9 preferably of V-shape is arranged to set in the fork 5 and projects rearwardly and forwardly thereupon when the 45 hod is set up for use any suitable means being provided for detachably connecting said section 9 with the fork 5, as for instance 50 bolts 10 and turn buttons or thumb screws 11. In the preferred construction the main section 9 is fitted with a shoulder rest comprising flanges 12 whereby it is secured in place by means of rivets 13 or the like and 55 a rest 14 of sufficient width to provide a maximum of comfort to the hod carrier and

to avoid relatively narrow edges which press into the shoulder of the carrier. In the preferred arrangement the rest 14 is recessed as indicated at 15 to fit the shoulder and 60 to facilitate the removal of the hod therefrom; the flanges 12 as illustrated constitute integral extensions of the rest 14.

The hod comprises further a supplemental section 16 which inwardly overlaps the main 65 section 9 and fits into the same and into the fork 5 as shown in Fig. 2, said supplemental section 16 constituting an extension of the main section 9 to complete the body of the hod and being detachably secured in position for instance by means of bolts 17 and turn buttons or thumb screws 18. Both the main section 9 and supplemental section 16 are provided with backs 19 and 20 respectively whereby one end of said sections is 70 closed, the back 20 of the supplemental section 16 being continued beyond the fork 5 preferably in the form shown in Fig. 2 and having its free edges as well as the free edges of the section 16 rolled or beaded as 75 indicated at 21 thereby avoiding any sharp or abrupt edges. An auxiliary section 22 is provided for detachable combination with the hod when the latter is to be used for carrying mortar, plaster or other semi-80 liquid material. This auxiliary section 22 is provided with sides which fit into the supplemental section 16 and with a back 23 which sets against the back 20 to form an extension thereof and which with the section 85 22 also preferably has its free edges rolled or beaded as shown at 24 in Fig. 2. The auxiliary section 22 may be detachably fastened in place in any convenient manner as 90 by means of bolts 25 and turn buttons or 95 thumb screws 26.

In some cases it may be desirable to fit the sections together as shown in Fig. 3 in which flanges 27 are formed, for instance by turning the material of which the sections are 100 constructed back upon itself, to provide recesses into which the edges of the contiguous sections are fitted; it will of course be understood that the flanges 27 may be otherwise constructed than as shown.

To adapt the hod especially for carrying mortar, plaster and the like and to prevent spilling thereof particularly when in a fresh fluid condition the open end of the main section 9 may be provided with a swinging door 28. The latter may be pivotally suspended from a bar or rod 29 which extends 105 110

transversely of said section 9, said door as shown being formed with a flange 30 which projects over the edges of the section 9 in the closed position of the door 28 and which 5 may be provided with a depression 31 arranged to cooperate with a projection 32 on the section 9 to lock the door against unintentional opening. When in its operative position the door 28 closes the open end of 10 the section 9 and thus prevents spilling or leaking of the contents, said door being easily released by simply exerting a pressure thereon or on the flange 30 sufficient to disengage the depression 31 and projection 32 15 from each other, the natural operation of dumping or emptying the hod causing said door to swing to an open position. The rod 29 may be located as in the drawings in which case the sides of the supplemental 20 section 16 are slotted at the proper points to fit over said rod or the latter may be so located in the main section 9 as to make such slots unnecessary.

When the hod is assembled for use as in 25 the illustration the sections 9, 16 and 22 constitute upward extensions of each other, which diverge upwardly along continuing lines as shown in Fig. 2, it being understood that the combined main section 9 and supplemental section 16 together constitute a 30 hod useful for certain purposes and that the auxiliary section 22 may be added to increase the capacity of the hod and to particularly adapt it for certain other purposes. 35 In addition to the frictional engagement of the sections with each other, the same are rigidly fastened together by means of the bolts and turn buttons so that the joints between sections are fluid tight; the pressure 40 of the material, when the hod is loaded, exerted against the sides of the several sections tends to press them together and thereby increases the tightness of said joints. The hod is preferably constructed of metal 45 and may be used in the same way and for the same purposes as an ordinary hod but differs therefrom in providing a greater capacity without discomfort to the hod carrier and in being capable of being easily 50 taken apart and knocked down. In the assembled condition of the parts the fork 5 straddles the connected sections 9 and 16 and is detachably connected therewith to increase the rigidity of the body of the hod. 55 The hod may be easily and quickly disassembled by simply disconnecting and removing the various bolts and turn buttons or thumb screws and then separating the sections from each other and from the fork; 60 the latter may be easily disconnected from the post or staff 8 by simply unscrewing the coupling 7, the post or staff being similarly taken apart as will be readily apparent. When knocked down the various parts of the 65 hod may be efficiently stacked or packed

together to occupy a minimum of space so as to be readily transportable or stored or so as to be easily accommodated in a mason's tool bag or kit. The shoulder rest 14 increases the comfort with which the hod 70 may be carried while the recess 15 because of its shape facilitates the forward rocking movement of the hod in removing it from the shoulder and thereby reduces the physical effort to dump or empty the hod. The 75 energy of the hod carrier is thus conserved with the result that his working capacity in a given time is increased.

The hod is simple in construction and may be produced at a relatively low cost and 80 because of its simplicity is not easily disarranged or disorganized.

Various changes in the specific forms shown and described may be made within the scope of the claims without departing 85 from the spirit of my invention.

I claim:—

1. A hod comprising a plurality of converging superimposed sections detachably fitted together, the lower edge portion of an 90 upper section projecting inside of the upper edge portion of the next adjacent lower section in the direction of convergence to form the body of the hod and a post connected with said body. 95

2. A hod comprising a V-shaped main section, a supplemental section of converging form having its lower edge portion projecting inside of and fitted into the upper edge portion of said main section in the direction of convergence to form the body of the hod, means for detachably securing said sections together and a post connected with said main section. 100

3. A hod comprising a V-shaped main section, a supplemental section of converging form having its lower edge portion projecting inside of and fitted into the upper edge portion of said main section in the direction of convergence to form the body of the hod, an auxiliary section of converging form having its lower edge portion projecting inside of and fitted into the upper edge portion of said supplemental section in the direction of convergence to increase the capacity of 110 said body, means for detachably securing said sections together and a post connected with said main section. 115

4. A hod comprising a plurality of converging sections detachably fitted together, the lower edge portions of the upper sections projecting inside of the upper edge portions of the next adjacent lower sections in the direction of convergence to form the body of the hod, means for detachably securing said sections together, a fork straddling said connected sections and detachably connected therewith to increase the rigidity of the body and a post connected with said fork. 120 125

PETER H. HARTMAN.
